UNITED STATES PATENT OFFICE.

WILLIAM P. STUBBLEFIELD, OF ST. LOUIS, MISSOURI, ASSIGNOR OF ONE-THIRD TO
GEORGE BAPTISTE, OF ST. LOUIS, MISSOURI.

STEP-MOLD.

1,147,826.

Specification of Letters Patent. Patented July 27, 1915.

Original application filed February 26, 1912, Serial No. 680,100. Divided and this application filed July 26, 1912. Serial No. 711,723.

To all whom it may concern:

Be it known that I, WILLIAM P. STUBBLEFIELD, a citizen of the United States of America, residing in the city of St. Louis and State of Missouri, have invented certain new and useful Improvements in Step-Molds, of which the following is a specification, this being a division of my application filed February 26, 1912, Serial No. 680,100.

This invention relates to step molds, and more especially to that class of molds that are used for the building of steps of concrete construction.

15 The primary object of this invention is in the combination and arrangement of parts in a device of this character whereby the step molds can be readily adjusted to their required pitch.

20 Another object is to provide improved side boards having segmental ends so that said side boards can be readily adjusted to the desired angle on which the steps are to be built.

25 A further object is to provide means whereby these side boards are self-adjusting to the base lines or foot of the steps and to the vertical line or wall to which the steps are to be built up.

30 A still further object is to provide improved adjusting means for these side boards so that the flight of steps can be made to any desired height; and by the segmental adjustment, any desired angle for the flight of steps can be obtained.

35 Other and further objects will appear in the specification, and be specifically pointed out in the appended claims, reference being had to the accompanying drawings exemplifying the invention, and in which,

40 Figure 1 is a side elevation of this improved adjustable side board construction of the step molds. Fig. 2 is a vertical section of Fig. 1, showing how this improved device is used during concrete step construction. Fig. 3 is an enlarged detail section on the line III—III, Fig. 1. Fig. 4 is an enlarged section on the line IV—IV, Fig. 3. Fig. 5 is an enlarged perspective view of 45 one of the tie rods. Fig. 6 is an enlarged fragmentary section on the line VI—VI,

Fig. 1. Fig. 7 is a perspective view of the base adjusting segment and its component parts.

The subject matter of this application 55 originally formed a portion of co-pending application Serial No. 680,100, filed February 26, 1912.

Referring to the drawings, the side boards are composed of sections 1, each of said sections being provided with a top flange 2, a bottom flange 3, and a lug 4 at each end, said lug 4 depending from the top flange 2 and adapting the sections to be detachably secured together by means of bolts 5, or 60 other suitable fastenings. When a number of these sections 1 are mounted together, the top and bottom sections 6 of each side board are preferably provided with arcuate flanges 7 to adapt them to bear upon the flanged 65 peripheries of adjustable segments or supports 8, said segments being provided, respectively, with flat edges 9 to adapt them to rest solidly against the horizontal and vertical surfaces (as shown in Fig. 1) while 70 supporting the side boards at the desired angle.

In order to provide improved adjustable means for tying the segments 8 and sections 6 and 1 together, in addition to the fastening 80 bolts 5, tie rods 10 are secured together and mounted through bearing lugs 11, said bearing lugs being mounted on the sections 1. Said bearing is provided with a set screw 12 for rigidly clamping the tie rods. The 85 lower segment 8 and its component part 6 are held together by the tie rod 13, said tie rod being pivotally mounted to the said segment by the stud 14, said tie rod 13 being mounted to the sections 6 through the bearing 15. Mounted on the tie rod 13, adjacent the stud 14, is a pocket 16 having a set screw 17 located therein, said pocket being for the purpose which will be hereinafter described.

90 Mounted in the peripheral flanges of the segment 8 adjacent the arcuate flanges 7 are slots 18 through which are mounted locking bolts 19, said locking bolts being carried by the arcuate flanges 7. Pivotally mounted on the upper segment 8 by studs 20 is a connecting sleeve 21, said sleeve having a pocket 100 22 located thereon and a set screw 23 mount-

ed in said pocket. Mounted on the upper section 6 is a bearing 24 through which the sleeve 21 is mounted. The peripheral flange of the segment 8 and arcuate flange 7 of the section 6 are locked in position by the lock bolt 25. Mounted in the bearings 15 and 24 of the section 6 are set screws 26.

In the operation of this improved device, when the desired angle of the flight of steps 10 to be constructed is given, the desired number of sections 1 are mounted together on the sectional tie rods 10. And the lowest sectional tie rod is mounted to the tie rod 13 of the lower segment 8, and the uppermost 15 tie rod is mounted in the sleeve 21 of the upper segment 8. The lower segment 8 is then mounted on the basing line, and the upper segment is mounted against a vertical line. Then this whole construction forming the 20 side boards is manipulated until the desired angle of the flight of steps has been obtained. Then, the locking bolts 19 and 25, along with the set screws 26, are tightened. Metallic stakes, such as 27, are then mounted 25 in the pockets 22 and 16 of the upper and lower segments 8, and are driven deeply into the ground, as clearly shown in Fig. 1. Then the set screws 23 and 17 are tightened 30 against the stakes. This will hold the side boards securely in position. After these side boards are in position, the step molds, or facing boards, such as 28, are mounted in between these side boards their proper distances apart. These facing boards, as 35 shown, are mounted in the L-brackets 29, said L-brackets being mounted to each other by the bolts 30, and are clamped against the side boards by the clamping screws 31. This embodiment shown of adjustable step 40 mold facing boards is immaterial to this invention, as any desired type can be used by merely fastening them to this improved construction of side boards, as this invention consists in the improved construction of being 45 able to aline the side boards to the desired angle of which the steps are to be constructed.

Referring again to Fig. 5, the tie rods 10 are provided at one end with the threaded 50 stud 32, and at their opposite end with a threaded socket 33.

What I claim is:

1. In a side board for step molding construction, the combination of pivotal segmental abutments located at the ends of said board, said abutments adapting said board to be disposed at different angles, said side board being constructed in sections adapted to be secured to each other, and means for locking said abutments to said side board, the inner faces of said sections adapted to aline flush with the inner faces of said abutments.

2. A step mold comprising side boards, and 55 adjustable abutments, said abutments adapting said side boards to be disposed at dif-

ferent angles with respect to horizontal and vertical supports, and locking means for engagement with the peripheries of said abutments for locking said abutments to their respective side boards, said side boards 70 and said abutments having their inner faces flush with each other.

3. A step mold comprising side boards, adjustable step forms carried by said side boards, and a segmental abutment adjustably 75 mounted at the ends of each of said side boards, the inner faces of said side boards adapted to aline flush with the inner faces of said abutments.

4. A step mold comprising side boards, adjustable step forms carried by said side boards, segmental abutments adjustably mounted at opposite ends of said side boards, and a sectional tie rod secured to each of said side boards, said tie rods having their 85 ends pivotally connected with said abutments.

5. A step mold comprising side boards, adjustable step forms carried by said side boards, segmental abutments adjustably 90 mounted at opposite ends of said side boards, and a sectional tie rod secured to each of said sections and having its ends pivotally connected with said abutments, said tie rod being provided with elongated pockets for 95 the reception of setting stakes.

6. In a knock-down form for step molding construction, a pair of sectional side boards, each section of each of said side boards being slidably mounted on a tie rod, a segmental abutment pivotally mounted on each end of said tie rods, and locking means carried by each end section of each of said side boards for rigidly securing said side boards to said abutments, said side boards having their inner faces flush with their respective abutments.

7. In a knock-down form for step molding construction, a pair of sectional side boards, each section of each of said side boards being mounted on a tie rod, each of said rods having a telescoping section, a segmental abutment pivotally mounted on each end of said tie rods, adjustable step forms carried by said side boards, and locking means for rigidly securing said side boards to said abutments.

8. A step mold comprising side boards, adjustable step forms carried by said side boards, segmental abutments adjustably mounted at opposite ends of said side boards, and a two-part tie rod secured to each of said side boards, one of said parts of said tie rods being slidably mounted on the other said part, said tie rods having their ends pivotally connected to said abutments.

9. In a knock-down form for step molding construction, a pair of side boards, each of said side boards comprising a series of sections detachably connected to each other,

a segmental abutment located at each end of said side boards, said sections of each of said side boards being mounted on a tie rod, said tie rods at their ends being pivotally connected to said abutments, an arcuate flange formed on each end section of said side boards, said flanges adapted to rest on said

abutments, and locking means carried by said flanges for rigidly securing said side boards to said abutments.

WILLIAM P. STUBBLEFIELD.
